[57] ABSTRACT

A steering-wheel cover comprising an endless perforated band is wrapped around a toroidal steering wheel and a lace attached to one edge of the band is wound around the wheel to hold the cover in place. The end of the lace carries a rigid metal strip or needle whose end is bent over the lace end so that it lies normally parallel to the lace. By means of this strip the lace end can be threaded through perforations on the cover for best holding characteristics. Spaced from the end of the strip opposite the bent-over end and inward of a longitudinal edge of the strip there is a cutting edge by means of which the free end of the lace is cut off. Advantageously the bent-over end of the metal strip is provided for best securing of the lace end.

STEERING-WHEEL COVER

FIELD OF THE INVENTION

The present invention relates to a steering-wheel cover. More specifically this invention concerns the type of cover described in my U.S. Pat. Nos. 3,489,031 and 3,530,739 and in U.S. Pat. No. 3,312,124 filed by Klaus Meier and myself for a Steering-Wheel Assembly For Automotive Vehicles.

BACKGROUND OF THE INVENTION

The types of steering-wheel cover described in the above-named patents comprise a pair of fluid-impermeable skins between which there is provided a porous spongy layer. Through-going perforations are provided over the entire surface of this sandwich so that the inner layer "breathes" as it is compressed during driving.

The cover is an endless band from one side of which extends a long lace and from the other side of which extends a short lace. The band is fitted around a toroidal steering wheel and the long lace is wound helically around the wheel over the band to secure the cover thereto.

When the entire cover has been so wrapped the free end of the long lace can be tied to the shorter lace. This results in a knot which, if it is not to come undone, must be relatively large. Such a knot can be extremely bothersome to the driver since it presents an uncomfortable lump somewhere on his steering wheel. Alternatively it has been suggested to thread the end of the lace in and out through some of the holes of the cover and then cut it off. Although this operation presents a smooth appearance and does indeed adequately secure the lace end, it is an extremely difficult operation. To manage this type of fastening the cover must be pinched and then the only slightly stiff lace end forced through two holes, it being necessary to chose two holes close enough together to allow this operation. At the best such an installation is a difficult and troublesome job.

OBJECTS OF THE INVENTION

It is therefore an object of the present invention to provide an improved steering wheel cover of the above-described general type.

Another object is the provision of such a cover which can be quickly and easily installed on a steering wheel without knotting.

SUMMARY OF THE INVENTION

These objects are attained according to the present invention by a steering-wheel cover of the above-described perforated type which has a single lace whose end is provided with a rigid needle portion itself provided with a cutting edge. This needle portion makes threading of the lace end in and out of a few holes on the cover a very simple operation, while its cutting edge allows the free lace end to be cut off without the use of any supplementary tools.

According to another feature of this invention the needle portion comprises a straight thin metal strip having one end bent over the lace end so that the lace end region normally lies along the strip. This strip can

be provided at its bent-over end with a tooth that passes through the lace end and projects into a corresponding hole on the facing region of the metal strip.

In accordance with yet another feature of the present invention the cutting edge is spaced from the ends of strip and inwardly from the longitudinal edge of the strip to prevent the user from accidentally cutting himself or the cover.

Such a steering-wheel cover assembly is installed on a toroidal steering wheel much as described above for the prior art except that the needle at the lace end is threaded through several of the cover's perforations. Thereafter the cutting edge on the needle is employed to cut off the excess, and the lace end carrying the needle is discarded. Thus the cover can be mounted rapidly without the use of any tools at all, and can be secured in what has been found to be the most advantageous manner possible.

DESCRIPTION OF THE DRAWING

The above and other objects, features, and advantages of the present invention will become apparent from the following description, reference being made to the accompanying drawing in which:

FIG. 1 is a perspective view of the needle and lace end of the cover according to the present invention;

FIG. 2 is a perspective view showing how the lace end of my cover is secured as the cover is installed;

FIG. 3 is a perspective view showing how the excess lace is cut off using the cover assembly according to my present invention; and

FIG. 4 is a longitudinal section through the lace end and needle according to the present invention.

SPECIFIC DESCRIPTION

As shown in FIGS. 2 and 3 the steering-wheel cover 1 is formed with a multiplicity of throughgoing perforations 2 and is wrapped around a toroidal steering wheel 3. The cover 1 comprises an endless band of synthetic-resin material as described in the above-mentioned patents. A lace 4 of synthetic resin extends from one edge of the cover 1 and is provided with a needle-cutter 6 which is attached to its extreme end 5.

The needle-cutter 6 is a straight rigid metal strip which is bent over at 7 around the end 5 so that it is generally J-shaped. In order to best secure the end 5, the end 7 is provided with a tooth 8 that is adapted to pass through the lace 4 and protrude into a hole or aperture 9 on the facing portion of the strip forming the needle 6.

A cutting edge 11 is formed on the strip 6 adjacent the end 10 thereof, but spaced therefrom, and also spaced inwardly on the strip 6 from a longitudinal edge 12 thereof. This edge 11 is simply formed by obliquely grinding away a portion of the strip 6 spaced from the end 10 thereof which is opposite to the bent-over end 7 of the strip. This recessing greatly reduces chances of accidentally cutting oneself on the cover 1, and also makes it easy to catch and cut the lace 4.

Installation of the cover 1 is carried out in the customary manner by wrapping the endless band around the wheel 3 and then winding the lace 4 around it helically. When the winding is completed, the end 10 of the strip 6 is grasped by the fingers and the end 7 is threaded through two of the holes 2 in the cover 1, under a turn

13 of the lace 4 around the wheel 3 and cover 1 as shown in FIG. 2. Thereafter the end 7 is grasped and the lace is pulled through. This threading can be carried out several times around the cover 1 for best holding characteristics, with the lace 4 overlying itself like turn 13 for best holding effect. When sufficient quantity of lace 4 has been threaded under and over the cover 1 this lace 4 is grasped adjacent a hole 2 and pulled snug, as shown in FIG. 3, and the cutter-threader 6 is grasped by its end 7 and the cutting edge 11 is employed to cut the lace 4 just adjacent the hole 2 from which it emerges. Then the lace end with the needle 6 is discarded and the installation is complete, the free end of the lace 4 having pulled back under the cover 1, or being caught under an edge of this cover 1.

In this manner an extremely neat installation is obtained. Even the least dexterous person can quickly and easily effect such an installation, without having to use any cutting instruments of his own to finish the job. Since the cutter is part of the original article there will be no reason why the user need not bother to make a good installation. He cannot lose the needle or cutter prior to mounting of the cover on the wheel so that proper installation is ensured.

I claim:

1. A steering-wheel cover assembly comprising:
a cover formed with a plurality of perforations and
adapted to be wrapped around a steering wheel;
a lace attached to said cover at one end and adapted
to be wound around said steering wheel over said
cover to retain same thereon; and
a rigid elongated body attached to the other end of

said lace and provided with a cutting edge, said body being dimensioned to pass through at least one of said perforations.

2. The assembly defined in claim 1 wherein said body has a bent-over end, said other end of said lace being clamped against said body by said bent-over end.
3. The assembly defined in claim 2 wherein said body is provided in the region of said bent-over end with a tooth projecting into said other end of said lace.
- 10 4. The assembly defined in claim 3 wherein said body is formed with an aperture aligned with said tooth, said tooth projecting through said lace into said aperture.
5. The assembly defined in claim 1 wherein said cutting edge extends only along a portion of the length 15 of said strip and is spaced from the end thereof opposite said bent-over end.
6. The assembly defined in claim 5 wherein said cutting edge is recessed inwardly from a longitudinal edge of said strip.
- 20 7. The assembly defined in claim 1 wherein said body has a bent-over end, said other end of said lace being clamped against said body by said bent-over end, said body being provided at said bent-over end with a laterally projecting tooth and being formed with a hole 25 in line therewith, said tooth projecting therewith, said tooth projecting through said lace and into said hole, said cutting edge extending only along a portion of the length of said strip and being spaced from one end thereof and recessed from a longitudinal thereof, said 30 lace adjacent said other end lying normally generally parallel to said strip.
